[57] **CLAIM**

The ornamental design for a housing for computer module, as shown and described.

DESCRIPTION

FIG. 1 is a perspective view of a housing for computer module showing our new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a front elevational view thereof;

FIG. 7 is a rear elevational view thereof;

FIG. 8 is an enlarged partial view of the mesh pattern shown on the top, front, sides and bottom of the module, the mesh being indicated in the other figures by cross-hatching for convenience of illustration.

FIG. 1

FIG. 8

FIG. 2
